UNITED STATES PATENT OFFICE.

PAUL V. AUSTIN, OF BUFFALO, NEW YORK.

APPARATUS FOR TREATING GRAIN OR THE LIKE.

1,377,743.

Specification of Letters Patent. Patented May 10, 1921.

Application filed May 31, 1919. Serial No. 301,025.

To all whom it may concern:

Be it known that I, PAUL V. AUSTIN, a citizen of the United States, residing at Buffalo, in the county of Erie and State of New York, have invented a new and useful Improvement in Apparatus for Treating Grain or the like, of which the following is a specification.

This invention relates to apparatus for use in treating seed, grain or the like for the purpose of destroying the spores of injurious fungous growths.

It has been customary before sowing oats, corn, wheat, or other grain or seed, to treat the seed or grain with a disinfectant, such for example as a solution of formaldehyde, for killing or rendering inactive the spores of the fungous growths known as "oat smut" "corn smut," "wheat rust" and other injurious growths. The usual method is to dip the grain into a receptacle containing the disinfectant. The grain must then be spread out and left standing for several days, and should be frequently stirred before it is dry enough to be put into bags, or before it will feed properly in the seed drills.

One object of this invention is to provide means for applying the liquid to the grain in the form of a fine spray or mist, while the grain is in motion. Another object is to subject the moving grain, after it has been sprayed, to a current of air for quickly drying it, so that it may be placed in bags, or used at once for seeding. Another object of the invention is to combine the spraying operation with the operation of cleaning and separating the grain, by attaching a suitable spraying device to a grain cleaning or fanning mill of any suitable sort wherein the grain before being subjected to the cleaning mill or separator is subjected to the spray and is then dried by the air current in the separator, so that when the grain leaves the separator it is ready for use as seed.

In the accompanying drawings:

Figure 1 is a central longitudinal sectional elevation on line 1—1, Fig. 2, of a fanning mill to which a spraying device has been attached for spraying grain in accordance with this invention.

Fig. 2 is a plan view, partly in section, thereof.

The accompanying drawings show a well known type of grain cleaning, separating or fanning mill which may advantageously be used in connection with this invention and

which includes the usual hopper A from which the grain discharges on the upper part or inclined ledge b of a reciprocating shoe B. The shoe is provided with separating screens b' b² to which the grain passes in a thin layer. All the grain passes through the screen b' and the coarse foreign matter, such as straw, chaff, small stones, etc., tails off over the end thereof, 60 while the screen b² is intended to separate small seeds and other small matter from the grain falling thereon from the screen b', the small material passing into the seed box b³. The grain flows over the surface of the 70 screen b² and drops, together with the grain passing through the lower end of the screen b', onto screens c c' of a lower reciprocating shoe C. In its passage from the upper shoe B to a lower shoe C, the grain is subjected to 75 a current of air from a fan D, the current being controlled by windboards, to effect a final separation or cleaning of the grain.

The purified grain passes over and through the screens c c' where it is further 80 subjected to the action of the air blast from the fan D, and tails off of the lower end c² of the shoe C. A separating, cleaning or fanning mill of any other suitable construction, or a device of any other kind in which 85 the grain is subjected to an air blast, may be used.

It has been found that by spraying or moistening the grain with the disinfectant as it passes upon the separating screens of 90 the fanning mill, a thorough destruction of the fungous growth is effected since the grain is agitated and rolled by the motion of the reciprocating shoes so that all parts thereof are sprayed or moistened. The spraying 95 may be effected by any suitable means capable of providing a fine spray or mist, the device shown comprising a tank F containing the disinfecting solution which is discharged under pressure into a hose or pipe f 100 having at its end a valve-controlled spray nozzle F'. The tank F is conveniently mounted in any suitable location on the separator, for example on the upper portion of the housing of the fan D, and the nozzle F' 105 is preferably secured to a cross bar f' of the separating frame by a clip or device f² in such manner that the liquid discharged therefrom is directed toward the stream of grain passing from the hopper. The pressure forcing the liquid from the tank F may be derived in any suitable manner, for ex-

ample by means of an air pump ¹⁸ by means of which air under pressure may be forced into the tank F. As the grain passes over the ledge b it spreads out into a thin layer, 5 and the individual grains or kernels roll on the surface thereof and on the screen b', thereby exposing their entire surfaces to the action of the spray from the nozzle F. By this means every grain or kernel that 10 may be infected, or which may carry deleterious spores will be thoroughly acted upon and rendered safe for use as seed. A spraying device of any other kind may be employed.

15 The grains or kernels, after being coated with the solution as explained, pass downwardly onto the lower shoe C and in their passage are subjected to the drying influence of the current of air from the fan D, and by 20 the time the grain reaches the end c² of the shoe C it is dry enough to be put into bags, or to pass freely through the seed drills. This results in a great saving in time, since 25 not only are the two operations of cleaning and disinfecting the grain completed simultaneously, but the time and labor usually required to dry the grain are saved.

I claim as my invention:

1. In an apparatus for treating grain, the 30 combination of means for cleaning and separating the grain, means for spreading the grain in a thin layer on said cleaning and separating means, means for treating the grain with an atomized spray of disinfecting agent as the grain passes onto the cleaning and separating devices, and means in said apparatus for simultaneously removing moisture from the treated grain and separating foreign matter therefrom while the 35 same is passing through said apparatus.

2. In an apparatus for treating grain, the combination of a shaking member at one end of which the grain to be treated is received and over which the grain travels in a thin 45 layer, means for directing a solution in the form of a spray onto the moving grain as it passes over the receiving end of said shak-

ing member, for completely coating each individual grain with said solution, said means including a reservoir for said solution from 50 which the solution is forced by air pressure, and means for removing some of the moisture from the grain and for separating foreign matter therefrom as it passes through said apparatus. 55

3. In an apparatus for treating grain, the combination of a hopper, an inclined reciprocating member beneath said hopper over which the grain passes as it leaves said hopper, a spray nozzle adjacent thereto for directing a spray of disinfecting material toward said inclined reciprocating member, said reciprocating member causing the grain to spread out so that the individual grains may roll thereon in the path of said spray and be thoroughly coated thereby, and means for passing a current of air through said apparatus to remove moisture from the grain as it leaves said reciprocating member and to remove foreign matter from the 70 grain. 60

4. The combination of a grain cleaning and separating device including shaking shoes provided with separating screens, means for blowing a current of air through said cleaning device for removing foreign matter from the grain, means for feeding a stream of grain to the receiving end of the upper of said screens, a valve-controlled spray nozzle for directing a spray of finely 75 divided disinfecting material to the grain at the receiving end of said upper screen, a tank containing said disinfecting material and which is connected with said nozzle, and means for supplying air under pressure to 80 said tank to force said material through said nozzle. 85

Witness my hand, this 26 day of May, 1919.

PAUL V. AUSTIN.
